UNITED STATES PATENT OFFICE.

GEORGE G. GARMAN, OF WASHINGTON, DISTRICT OF COLUMBIA.

ELECTRIC SYSTEM FOR PIPE-ORGAN-COUPLER CONTROL.

Application filed June 9, 1926. Serial No. 114,779.

This invention relates to certain new and useful improvements in controls for electric and electro-pneumatic actions of pipe organs.

It is recognized that the usual couplers for pipe organs connect the tone qualities of one keyboard with the tone qualities of another, so that all of the "voices" or parts of polyphonic music being played upon a manual are connected and merged with corresponding "voices" of another keyboard without regard to their relative importance in the musical effect to be produced.

The object of this invention is to provide a coupler which will function on any given "voice" or "voices" of polyphonic music, thus eliminating the necessity for the player attempting to play on two manuals of the instrument with the fingers of one hand. A further object is to provide a coupler which will automatically connect any "voice" or "voices" on any keyboard with any other keyboard, thus providing a means of increasing the volume or intensity of tone or of contrasting the tone quality of any predetermined "voice" or parts of the music relative to the other parts at the discretion of the performer.

Another object of this invention is to provide a means of connecting or coupling any device outside of the organ with the instrument, as for example chimes in a tower, so that they will be energized or made to function with any predetermined voice or voices of the music, simultaneously with the playing of the organ and without disturbing the instrument itself.

With the foregoing and other objects in view, the invention consists in the novel combination of parts and in the details of construction hereinafter set forth in the specification and appended claims, certain embodiments of my invention being illustrated in the accompanying drawings, in which:

Figure 1 is a diagrammatical illustration of my electrical coupling device for selectively coupling one voice;

Figure 2 is an illustration of a similar device for coupling selectively either of two or both voices;

Figure 3 is an illustration of a similar device for coupling selectively three voices, and any one or two of said three voices.

Referring more particularly to the drawings, Figure 1 shows an electrically excited coupler which will function for only the highest (right hand side) key which is de-

pressed on the instrument at any given instant. (The terms "highest" and "lowest" used throughout this specification are conventional musical terms indicating relative position to right and left hand side of the keyboard or manual.) In all three figures of the drawings corresponding parts bear the same numbers.

Conductors 4 and 5 are the electrical lead wires already within the instrument as a key circuit. Switch 1 is the control switch used to energize the device when it is desired to put it into operation, and on the console of the instrument takes the form of a tablet, draw-knob, button or other device to correspond with the other features of the console. 6, 7, 8, and 9 represent a plurality of key contacts (the standard keyboard having sixty-one of them) for any manual. 10, 11, 12 and 13 are electric coils, the inductance of which represents the function or work which is ordinarily and usually performed by the closing of the key contacts 6, 7, 8, and 9. Coils 10, 11, 12 and 13 together with conductors 4 and 5 form part of the instrument with which the invention operates. 14, 15, 16 and 17 are relays whose armatures 14', 15', 16' and 17' (when control switch 1 and any or all of the plurality of key contacts 6, 7, 8, and 9 are closed) complete the circuit from the power lead 4, through the induction coils 18, 19, 20 and 21 which represent the function or work to be performed by the coupler being described.

To explain the operation of Figure 1; if switch 1 is open as shown in the drawing, and all four keys 6, 7, 8 and 9 are closed, then current will flow through the line 31 and energize all the relays 10, 11, 12 and 13, and the coupler device is inoperative. If, however, switch 1 is closed, and key contacts 6, 7, 8, and 9 are also closed, then (assuming lead 4 to be "positive" and lead 5 "negative") current will flow through the line 32, through relays 10, 11, 12 and 13 as before, and in addition through switch 1 and relays 14, 15, 16 and 17, thereby causing their movable armatures 14', 15', 16' and 17' to drop. This breaks the continuity of the electric conduction line connecting the armatures at four points; so that, while a contact at points 18', 19', 20' and 21' is also made by each relay respectively the induction coils 18, 19 and 20 can not be energized as the current will flow through switch 1, line 32, the armature of relay 17, armature 17'; through the contact

21' to the induction coil 21, and back to lead 5. It is shown that only that closed key 9 which is located furthest to the right on the drawing will permit energizing its corresponding induction coil, these being the ones whose inductance represent the function or work to be performed by the coupler.

It will be seen that by simply reversing the device symmetrically with respect to the two 10 sides the same device may be made to operate in exactly the same manner for the closed key contact which is furthest to the left hand side.

A further development in Figure 2 shows the method of coupling that key on the instrument which is second from the right of those depressed at any given instant. Relays 22, 23, 24, and 25 are shown for convenience in drawing as having two armatures each, 24', 38, 25' and 37 etc. respectively. Relays having but one armature may be used in actual practice. Switch 2 is used to energize the invention when it is desired to put into operation a device for coupling the next to highest voice. Switch 2 takes the form on the console which will correspond to the other tablets, drawknobs, etc. on the instrument. Switch 30 closes with either or both of switches 1 and 2 to energize the relays 22, 23, 24 and 25.

If in Figure 2 control switches 2 and 30 are 30 closed together with key contacts 6, 7, 8 and 9, then (as in Figure 1) relays 22, 23, 24 and 25 will be energized by current flowing through switch 30. Current will also flow from lead line 4 through line 31, through induction coils 10, 11, 12 and 13, through keys 6, 7, 8 and 9 back to lead line 5. At the same time each relay 22, 23, 24 and 25 will by means of their armatures break two contacts and make two other contacts. Current will then 40 flow from lead line 4 through switch 2, line 33, to the armature of relay 25 (armature 37, shown as the upper armature on the drawing). Here, on account of the operative positions of both relays, the current will be 45 transferred from line 33 connecting armatures opposite to switch 2 and will pass over to line 32 by means of contact 35. As contact 25' is broken it must proceed from this point in only one direction to armature 24', 50 to contact 20' and on through induction coil 20 which is one of the coils of the coupler.

Switch 1 in Figure 2 puts into potential operation the same device as shown in Figure 1. Figure 2, therefore, shows the method 55 of using the device either to couple the highest or next to highest keys which are depressed by closing control switches 1 or 2 as desired. As in Figure 1, Figure 2 may also be reversed symmetrically to couple either the lowest or 60 next to lowest keys which are depressed. Hence in four part music by the use of the apparatus described in Figure 2 it is possible to couple any or all of the voices to any other manual, sets of pipes or bells, etc., within or 65 outside of the instrument by simply closing

the proper switches corresponding to 1 and 2 etc. Switches 1 and 2 will for convenience be placed among the mechanical stops on the instrument's console.

Figure 3 is a further development showing 70 a method of coupling the third key from the highest which is closed. This device is put into operative condition by closing switch 3 in the same manner in which control switches 1 and 2 in Figures 1 and 2 are closed—switch 75 30 closing with either of switches 1, 2, or 3.

Relays 26, 27, 28, and 29 are shown as having three armatures. The use of relays with one armature is permitted as part of the invention. Closing switch 3 energizes line 34 80 opposite it through the relay armatures when the relay armatures are in the inoperative position. When one or more key contacts (6, 7, 8, 9) are then closed, the corresponding relay of the highest closed one such as 9 85 will cause its armature 40 to break the line 34 and transfer the electrical potential to the line 33 opposite to and connected to switch 2. Further functioning of the apparatus shown in Figure 3 is the same as that shown 90 in Figure 2. The coupler circuit is, therefore, from lead 4 to switch 3, through line 34, armature 40, contact 44, line 33, armature 38, contact 36, line 32, relay 27', contact 19', induction coil 19 which it was desired to energize in accordance with the invention, back 95 to lead line 5.

As a further explanation assume that in Figure 3 switches 3 and 30 are closed, and key contacts 6, 7, and 8 are closed. Then current 100 will pass from lead 4, through switch 30, through relay coils 26, 27 and 28 back to lead line 5. Simultaneously current will pass through the coupler circuit from line 4, through switch 3, line 34, armature 40, along 105 line 34 to armature 41, through contact 45, along line 33 to armature 39, contact 43, line 32 to armature 26' to induction coil 18 which it was desired to energize in accordance with the invention, thence back to lead line 5. 110 Armature 42 will not be energized on account of the break made in line 34 by armature 41. Contact 46 will be "dead" due to the break in line 33 caused by armature 39, and because 115 armature 42 is not energized.

The apparatus in Figure 3 may also be reversed with respect to right and left sides so that coupling may be obtained for the lowest, second to lowest, third to lowest, third to highest, second to highest, or highest part or voices as played upon the manual of the instrument. Likewise any two or more of these 120 couplers may be used simultaneously.

In a similar manner the invention may be 125 extended for any number of voices as may be desired.

Having thus described my invention, I claim:

1. In an electrical system for controlling 130 the operations of a pipe organ, a plurality of

mechanical coupler stops which are adapted to couple selectively any one or more voices or parts of polyphonic music being played on one manual to any other manual or musical devices located either within or outside of the instrument.

2. In an electrical system for controlling the operation of a pipe organ, means for selectively coupling one or more voices or parts of polyphonic music being played on one manual to any other manual or musical devices located within or outside of the instrument.

3. In an electrical system for controlling the operation of a pipe organ, means for selectively coupling one or more voices of polyphonic music being played on one manual to another manual or musical devices located within or outside of said organ, said means comprising a main line conducting current to a plurality of induction coils in parallel, a switch operated line, a plurality of relays arranged in parallel in connection with said switch, a plurality of armatures in said switch line adapted to be actuated by said relays for selectively energizing one or more of said induction coupler coils into operative condition in circuit with said switch upon the closing of the key contact in the same local circuit with the selected coupler.

4. In an electrically controlled pipe organ a means for accentuating by increase in vol-

ume or change of tone quality selectively any one or more parts of polyphonic music being played upon a manual, said means consisting of a main line conducting current to a plurality of induction coils in parallel, a switch operated line, a plurality of relays arranged in parallel in connection with said switch, a plurality of armatures in said switch line adapted to be actuated by said relays for selectively energizing the controlling features of other manuals or musical devices located either inside or outside of the instrument, a plurality of mechanical stops arranged upon the console of the instrument and adapted to control the action of said accentuation means.

5. In an electrical system for controlling the operation of a pipe organ, means for selectively coupling one or more parts of a chord played on one manual to any other manual, said uncoupled parts, while played simultaneously with said coupled parts, being sounded only on the manual on which they are played.

6. In an electrical system for controlling the operation of a pipe organ, means for selectively coupling one or more parts, to the exclusion of the remaining parts, of a chord played on any manual to any other manual, said uncoupled parts being sounded only on the manual on which they are actually played.

In testimony whereof I affix my signature.

GEORGE G. GARMAN.
